DESIGN FOR A ROLL WARMER OR THE LIKE

Stephen A. Platt, Decatur, Ill., assignor to U. S.
Manufacturing Corporation, Decatur, Ill.

Application March 27, 1939, Serial No. 83,852

Term of patent 7 years

To all whom it may concern:

Be it known that I, Stephen A. Platt, a citizen of the United States and a resident of Decatur, in the county of Macon and State of Illinois, have invented a new, original, and ornamental Design for a Roll Warmer or the like, of which the following is a specification, reference being had to the accompanying drawing, forming part thereof.

In the drawing:

Fig. 1 is a side elevational view of a roll warmer showing my design;

Fig. 2 is a similar view with the roll warmer turned through an angle of 90° and

Fig. 3 is a top plan view.

I claim:

The ornamental design for a roll warmer or the like, substantially as shown.

STEPHEN A. PLATT.
